MIXING AND BLENDING APPARATUS

Samuel H. Vasold, Bridgeport, Mich.

Application June 15, 1950, Serial No. 168,180

2 Claims. (Cl. 259—180)

1

This invention relates to a non-segregating mixing and blending apparatus for use in industry in general.

One of the prime objects of the invention is to design a non-segregating mixing and blending apparatus of simple, practical, and economical design by means of which bulk materials of all kinds may flow, by gravity, through said apparatus without segregation and be effectively mixed and blended without the use of power driven machinery or other manual effort.

Another object of the invention is to design an inexpensive, non-segregating mixing and blending apparatus which provides both a deflecting and a reflecting action for the material as it flows therethrough, so that the particles are not segregated but are effectively and rapidly mixed simultaneously with the blending.

It is well-known in the art that where materials are conveyed, handled or stored in individual bins or hoppers, the larger particles tend to separate from the smaller and gravitate toward the bottom of the bin, the light particles separate from the heavy so that localized spots or areas contain unmixed materials and a condition termed "segregation" results; consequently, material drawn from the bin or hopper is not uniform or properly mixed and blended.

The above-described condition is particularly noticeable where materials are stored for prolonged periods of time, so that when drawn from the bins or hoppers for distribution or treatment, uniformity cannot be obtained.

With the above and other objects in view, the present invention consists in the combination and arrangement of parts, hereinafter more fully described, illustrated in the accompanying drawing and more particularly pointed out in the appended claims, it being understood that changes may be made in the form, size, proportion, and minor details of construction, without departing from the spirit or sacrificing any of the advantages of the invention.

In the drawing:

Fig. 1 is a vertical, part-sectional view through my new mixing and blending apparatus.

Fig. 2 is a top, plan view thereof.

Fig. 3 is a transverse, sectional plan view taken on the line 3—3 of Fig. 1.

Fig. 4 is a view similar to Fig. 3 taken on the line 4—4 of Fig. 1 and looking in the direction indicated by the arrows.

Referring now more specifically to the drawing in which I have shown the preferred embodiment of my invention, the apparatus comprises a pair

2

of conical-shaped, concentrically arranged shell members 8 and 9 respectively, suitably spaced-apart and supported in spaced relation by means of guide supports or baffles 10 which are welded to the inner and outer shell respectively to form a passage 11 therebetween, and similar inverted, conical-shaped shell members 12 and 13 are placed in opposed relation to the members 8 and 9 with their frustums welded or otherwise connected to the frustums of the upper sections, so that the passage 11 is continuous from end-to-end of the apparatus.

A tubular extension or spout 14 forms an extension of the upper end of the outer shell 8 and can be connected to a hopper or bin (not shown) in any desired manner.

The guides or baffles 10 are mounted in the passage 11 in radially spaced relation, the upper ends being spaced slightly below the vertex of the inner shell 9 so that as the material is fed to the apparatus, the vertex of the shell spreads the stream of incoming material so that it is uniformly spread between the guides and around the circumference of the shell, fanning out in its downward travel and as the distance between the guides increases so that when it reaches a point of largest diameter, the material will flow in a wide but thin stream, thence striking the outer shell 12 of the lower conical shaped members 12 and 13 and thence being directed inwardly.

The lower conical-shaped section 12 is also provided with a tubular extension 15 which can be connected to a receptacle or bin (not shown) and into which the mixed and blended material is discharged, and I wish to direct particular attention to the fact that as the material flows, by gravity, between the upper shells 8 and 9 and reaches the frustum of the sections 12 and 13, a positive deflecting and mixing action takes place, the material being spread over the entire surface of the shell directly below the guides. There is no separation or segregation and the passage through the lower sections 12 and 13 brings the materials together so that a thorough mix and/or blend is obtained.

For more effective mixing, I can, of course, provide a plurality of the units in superimposed relation in which the discharge spout of one unit connects to the intake spout of the next unit.

The apparatus has great capacity; it can be easily manufactured and assembled, and can be produced in any size necessary to suit the demand.

From the foregoing description, it will be ob-

vious that I have perfected a very simple, practical and inexpensive non-segregating mixing and blending apparatus for treating materials of a fragmentary or granulated classification.

What I claim is:

1. A non-segregating mixing and blending apparatus comprising concentrically arranged pairs of spaced-apart inner and outer conical shells secured together at their bases to form a single unit, with a continuous passage between said pairs of shells and extending from end-to-end of said apparatus, and a plurality of radially disposed spaced-apart straight baffles provided in the passage in the upper pair of inner and outer conical shells and spacing them from each other.

2. A gravity non-segregating stationary apparatus of the character described comprising, a pair of concentrically spaced and arranged inner and outer conical shells, a similar pair of inverted concentrically arranged inner and outer shells secured to the first-mentioned pair with

their bases secured in abutting relation to form a unitary structure, a passage between the inner and outer shells and extending from end-to-end of the apparatus, and a plurality of radially spaced guide baffle members secured in said passage between the upper pair of concentrically arranged shells for uniformly distributing the volume of material flowing through the apparatus.
